UNITED STATES PATENT OFFICE.

WILLIAM J. GEDDERT, OF ALLIANCE, OHIO, ASSIGNOR TO AMERICAN STEEL FOUNDRIES, OF NEW YORK, N. Y., A CORPORATION OF NEW JERSEY.

CAR-COUPING.

1,169,796.

Specification of Letters Patent.

Patented Feb. 1, 1916.

Application filed March 17, 1913. Serial No. 754,712.

To all whom it may concern:

Be it known that I, WILLIAM J. GEDDERT, a citizen of the United States, and resident of Alliance, in the county of Stark and State 5 of Ohio, have invented certain new and useful Improvements in Car-Couplings, of which the following is a specification.

My invention relates to car couplers and has particular reference to a novel knuckle 10 throwing device for use in connection therewith.

It is a general requirement of many of the railroads that couplers applied for use on their cars must be equipped with knuckle 15 throwing devices; that is, some device by means of which the trainmen may throw the knuckle of the car coupler without the necessity for passing between the cars. Many such devices have been suggested but 20 in view of the limited space within which a thrower must be installed, the weight of the knuckle and the consequent resistance to movement due to rusting, etc., such devices have not proven altogether satisfactory.

25 One of the objects of my invention is to provide a knuckle thrower which shall be extremely simple; which shall operate on the knuckle tail at a point where the greatest leverage may be secured; which shall not cause the movement of the knuckle by 30 reason of frictional or cam engagement and which may be so located as to not interfere with the proper operation of the lock or lifter.

35 The invention will be more readily understood by reference to the accompanying drawings, wherein,

Figure 1 is a plan view of a coupler embodying my invention, the top wall of the 40 coupler being broken away; Fig. 2 is a similar view showing the knuckle completely thrown and illustrating a corresponding position of the knuckle thrower; Fig. 3 is a longitudinal, vertical section through the coupler with the parts in normal position; Fig. 4 is a similar view showing the lock in lock-set position, and Fig. 5 is a similar view 45 showing the relation of the parts corresponding to that of Fig. 2; that is, with the knuckle fully thrown.

50 Referring more particularly to the drawings it will be seen that my invention is combined with a coupler having a head 10, provided with vertical bearings 11, 12, to the rear thereof the former having an

open side. On the front wall of the head in the upper portion is provided an abutment or hook 13, with which the lock may coöperate as will be later described. Mounted within the coupler head on a pivot pin 60 14, is a knuckle 15, having a tail portion 16, the rear of which is cut away to form the curved bearing 17, with which the knuckle thrower coöperates. The portion of the knuckle tail which is not cut away forms a 65 pulling hook 18. It will be noted that by such construction the knuckle thrower may underlie a portion of the knuckle tail and thereby be held against possible displacement. Mounted within the coupler head and 70 adapted for vertical movement therein is a locking-block 19, having a groove 20, in its upper forward portion which coöperates with the abutment or hook 13, on the coupler wall. On the lower rear portion of 75 the lock is a downwardly projecting foot 21, having a bulbous lower end 22, and a notch 23. The notch is adapted to coöperate with a ledge 24 on the coupler wall in order to secure the lock-setting function as 80 shown in Fig. 4. I provide a lifter 25 having an enlarged lower end 26, slotted to accommodate the staple 27 on the lock. The lower end of the lifter is adapted for movement relative to the lock and in the normal 85 position underlies a ledge 28, on the coupler head to secure an anti-creeping function.

The thrower of my invention is provided with prongs 29, 30, and with trunnions 31, 90 adapted to seat in the bearings 11, 12, in the coupler head. Thus the thrower is mounted for horizontal swinging movement. The short arm 29 of the thrower is adapted to be contacted by the bulbous end 22, of 95 the foot 21, after the lock reaches the position shown in Fig. 4. Further movement from the position of Fig. 4 will cause the lock to oscillate on the point 13 as a pivot thus swinging the lower portion of the lock rearwardly and causing the rotation of the 100 thrower. The long arm 30 of the thrower is curved as shown and has a point bearing on the curved face 17 of the knuckle tail. The knuckle is thus moved outwardly by 105 rolling contact. The first application of power tending to rotate the knuckle is made at a point farthest removed from the pivotal point of the knuckle thus giving the greatest leverage.

110 It will be seen that the construction is

extremely simple and rigid; may be easily assembled or the parts removed and is thus particularly suited for general railway use.

It is obvious that modifications may be made in the construction shown and such modifications as are within the scope of my claims I consider within the spirit of my invention.

I claim:

of being raised and lowered with respect to its locked position, the top face of the lock being provided with a fulcrum portion located in rear of the front face of the lock, 45 said front face of the lock being free from projections, the front interior wall of the coupler head having a fulcrum shoulder lying in the path of upward movement of the fulcrum portion on the top of the lock to co- 50 operate therewith and cause the lock to tilt on said fulcrum shoulder as a center, said interior front wall of the coupler head being free from projections below the fulcrum shoulder thereof and constituting a guide 55 for the lock to direct the fulcrum portion thereof to the fulcrum shoulder of the head, and a knuckle opener disposed in the path of movement of a portion of the lock during 60 the tilting thereof for actuation by the tilt- 65 ing of the lock.

4. A car coupler having a coupler head and a bodily movable knuckle lock capable of being raised and lowered with respect to its locked position, said lock being provided on its top face with a transverse groove located in rear of the front face of the lock, said front face of the lock being free from projections, an interior wall of the coupler head having a fulcrum shoulder located in the path of and to coöperate with the groove of the lock during the upward movement of said lock to tilt the lock on said fulcrum shoulder of the coupler head as a center, and a knuckle opener disposed in the path of movement of a portion of the lock during the tilting thereof for actuation by the tilting of the lock.
